Gilmour Joslin Boston, Massachusetts
Letters Patent No. 30, dated May 7th 1845

The Schedule referred to in these Letters Patent and making Part of the same. —

To all whom it may concern: Be it known that J. Gilmour Joslin of the City of Boston, in the State of Massachusetts, have produced a new and useful Design, shape, or Configuration of a Tripod or Stand, of cast iron, or other metal, which Tripod or Stand, is intended to support Terrestrial and Celestial Globes, and other articles to which it may be adapted; and I do hereby declare that the following is a full and exact description thereof:

In the accompanying Drawings, I have represented the shape or configuration of my Tripod, when the respective pieces of which it is composed are put together, and I have also shown the shape or configuration of the respective parts thereof, separately and individually.

Fig. 1, is a view of the whole, in perspective, when the parts are put together, and are ready to receive the modern horizon, or to be surrounded by any other article.

Fig. 2, is a vertical section through the centre of fig. 1; and the other figures represent the shape and configuration of the connecting parts in detail; a. a. a. are the legs, the upper ends of which are received within a bell-formed piece b. b. the shape of which is distinctly shown in the section, and the configuration of the under side of which, is represented on an enlarged scale in fig. 3. On the middle of the under side of this piece, there is cast a circular projecting pin, having in it, three notches c. c. c. Fig. 4. shows the shape of the upper end of one of the legs, drawn on a scale corresponding to fig. 3; d. is a pin cast on it which fits into one of the notches, e. fig. 3, the flat top of said leg resting on the circular centre piece, and on the ledges e. e. e. cast on the piece b. b. for that purpose. To the body h. of the stand, I give the shape shown in fig. 1 and 2, its exterior being ornamented with leafing, and this is surmounted by a cap f. shown on an enlarged scale, in fig. 5 and 6; the former being a sectional and the latter a bottom view thereof; a rod g. is cast in this cap, which is to extend down through the hollow body of the swelled column h. serving, by means of a washer and screw nut, seen in fig. 2. to confine all the parts together. The cap f. is made to receive and confine the branches i. i. i. which sustain the wooden horizon, when used for globes. Fig. 7 represents the shape of the lower end of one of the arms i. fig. 8. being a top view of the same, upon these ends is cast a lip or pin j. which is received within the hollow k. of the cap piece f. whilst its body passes into the notches l. l. of said cap piece. The cap piece f. is so shaped, as shown at l', as to pass into

Dec. 30

h, which has within it a fillet or ledge, upon which the arms rest, they being strained down by the nut which confines the legs.

Having thus fully set forth the shape, or configuration, of the respective parts of my Tripod, as well as of the whole in their combined state, what I claim as new therein is the special and peculiar shape or configuration, which I have given to the respective parts and, consequently, to the whole instrument, as herein represented; that is to say, I claim, conjointly, the manner of shaping the upper ends of the legs, the bell-formed piece b. & the cap piece t, and the parts of the arms i. e. which are to fit thereto, and to be received within the trumpet-shaped mouth of the body or column h.

I am fully aware that various articles of metal have been so formed as to have their legs or other parts, connected together by mechanical arrangements similar to that by which I connect the respective parts of my Tripod, and I do not, therefore, claim to have invented any thing which could become the subject of a Patent for a combination of parts substantially new in their general combination and arrangement, but I limit my claim, as above stated, to the special shape, or configuration of the respective parts as devised by me, and herein set forth.
